UNITED STATES PATENT OFFICE.

JOHN ROBERT SPENCER, OF BARTOW, FLORIDA.

DESIGN FOR A BABY-CARRIAGE BODY.

41,354.

Specification for Design.

Patented May 2, 1911.

Application filed February 10, 1910. Serial No. 543,195. Term of patent 7 years.

To all whom it may concern:

Be it known that I, JOHN R. SPENCER, a citizen of the United States, residing at Bartow, in the county of Polk and State of Florida, have invented a new, original, and ornamental Design for Baby-Carriage Bodies, of which the following is a specification, reference being had to the accompanying drawing, forming part thereof.

Figure 1 is a perspective view of the baby

carriage body showing my new design. Fig. 2 is a top plan view of the baby carriage body showing my new design.

I claim:

The ornamental design for a baby carriage body, as shown.

JOHN ROBERT SPENCER.
